UNITED STATES PATENT OFFICE

2,567,321

DRILL STEM TESTER

Leo Courter, Oklahoma City, Okla.

Application September 26, 1946, Serial No. 699,489

26 Claims. (Cl. 166—1)

1

This invention relates to novel and useful improvements in a drill-stem tester and more specifically pertains to an apparatus that is automatically operable to close off and seal a portion of a well bore for securing information regarding the ability of a formation to produce water, oil, or gas.

The principal objects of this invention are to provide a testing apparatus which may be applied to existing well bores, whether cased or uncased, by merely attaching the same to the end of a drill stem; which is fully automatic in its operation; which is operable to seal or close the bore at any desired location therein for sealing off a pressure-producing formation below said seal; which has an automatically applied and released sealing means; wherein a predetermined time interval is established before the sealing means is completely applied; wherein a sample of the formation may be automatically secured after the device is seated in the bore; wherein a safety means is provided for insuring closing of the sampling device before the seal is removed and the apparatus withdrawn from the bore; and wherein the foregoing are obtained by an efficient, easily employed and durable apparatus;

These, together with various ancillary objects which will later become apparent as the following description proceeds, are realized by my device, one embodiment of which has been illustrated, by way of example only, in the accompanying drawings, wherein like numerals indicate similar parts throughout the various views, and wherein:

Figure 1 is a view in vertical elevation illustrating the insertion of my device in a well bore;

Figure 2 is an elevation of the upper portion of my apparatus, parts being shown in section to more clearly depict the structure of the same;

Figure 3 is a view similar to Figure 2 but showing the lower portion of my device;

Figure 4 is an elevational view of the central unit forming a part of my device;

Figure 5 is an elevational view of an intermediate unit forming another part of my device;

Figure 6 is an elevational view of an outside member forming a part of my device;

Figure 7 is a view similar to Figure 3, but showing the various parts in a different position of operation;

Figure 8 is a view in elevation of a portion of the device illustrating the sealing means in its engaged position;

Figure 9 is a horizontal sectional view taken

2

substantially upon the section line 9—9 of Figure 2; and

Figure 10 is a horizontal sectional view being taken substantially upon the section line 10—10 of Figure 2.

Referring now more specifically to the attached drawings, wherein similar numerals indicate like parts throughout the several views, numeral 10 denotes generally my novel tester which consists of a series of concentric and telescopic elements and which is shown positioned in a well casing 12, although it will be understood that the apparatus is fully susceptible of use with uncased wells or bores. The tester includes an axial, tubular supporting member 14, (see Fig. 4), a telescoping intermediate unit 16, (see Fig. 5), and an outer or sealing element 18, (see Fig. 6).

A general, brief statement of the manner of functioning of the device will assist in understanding the structure to be subsequently set forth. The axial, or inner member indicated at 14 and shown in elevation in Figure 4, is intended to be directly secured to the conventional, tubular drill stem that is now commonly employed in drilling or in working deep wells. The intermediate member, indicated at 16 and shown in elevation in Figure 5, is mounted upon and surrounds a portion of the member 14, and has relative longitudinal, controlled movement thereon in a manner to be subsequently set forth. The outer member, 18, indicated in elevation in Figure 6, is mounted upon and surrounds the member 16, and also the lower end of member 14, and constitutes the sealing means which is intended to completely seal, at will, a selected portion of the bore of the well or casing as desired and as set forth hereinafter. The structure is so designed that when the device is gradually lowered into a well casing or bore, a bypass is provided about and within the sealing means to permit the free passage and flow of the drilling mud usually found in such a bore in order to facilitate the passage of the device into and out of the well. As soon as the lower end of the sealing means has seated upon the bottom of the well bore, the downwardly descending axial inner member 14 successively performs a series of functions in timed relation, to thereby close the bypass extending through the sealing member, expand the latter into sealing engagement with the walls of the bore of the well, and finally, after a predetermined time interval, open a valve port establishing communication between the interior of the drilling stem, the axial tubular member 14,

50 55 and the interior of the well bore below the seal-

ing means for the purpose of sampling or testing the pressure, rate of flow, composition of the product of the well bore, or any other desired data. The device is so designed that when the testing or sampling of the productive capacity of the well formation is completed, the drilling stem, together with the axial tubular member 14, is slowly withdrawn or lifted from the well bore, producing in timed sequence, first, a closing of the valve port of the testing element, a reopening of the interior bypass around the sealing member, and then a collapse and release of the sealing engagement with the walls of the bore, whereupon the entire device may be freely withdrawn from the drilling mud in the bore.

Attention is now directed, first, to the construction of the axial tubular member 14, as shown best in Figures 2, 3 and 4. This unit comprises, at its upper portion, a tubular sleeve 22, having its upper portion externally threaded, as at 24, for engagement with a tubular drilling stem of conventional and known design. At its lower end, the tube 22 is secured in the interior bore of a piston 26 as by means of screw threads 28. This piston is provided with a known type of packing or sealing means indicated at 30, which is retained in a groove in the external surface of the piston as by a packing gland 32. The piston is provided with an internal bore 34 in free communication with the interior of the tubular member 22, and receiving the upper end of a depending sleeve or tube 36, by means of any suitable fastening agency, as, for example, screw threads or the like. The depending tube or sleeve 36 adjacent its lower end is provided with a series of ports or apertures 38 establishing communication between the interior and exterior thereof for a purpose to be later set forth, and is closed at its lower end, as by a plug or cap 40, a dome-shaped housing or sleeve 42 being detachably positioned upon the lower portion of the cap 40. This sleeve 42 is provided with a suitable port 44 for the purpose of establishing free communication between any suitable instrumentality such as pressure, temperature, or other measuring devices, not shown, which may be housed within the sleeve 42. As so far described, the unit 14 operates as a single, rigid member, which is directly attached to the lower end of the drilling stem and is raised or lowered thereby.

Attention is next directed to the intermediate unit 16, shown best in Figures 2, 3 and 5. The member 16 at its upper end comprises a hydraulic chamber formed by an upper sleeve 46 and a lower sleeve 48, connected by an intermediate bushing 50, as by screw threads upon the external surface of said bushing and the internal surfaces of said sleeves 46 and 48. The upper end of sleeve 46 is provided with a gland 52, having an annular aperture 54 adapted to surround, in spaced relation, the tubular member 22. Inwardly extending lugs 55 constitute grinding ribs slidably engaging and centering the tube 22 in the aperture 54 and member 46. At its lower portion, and extending inwardly from the interior surface thereof, the bushing 50 is provided with a plurality of radially extending ribs 56 constituting stop means for engagement with the upper end of the piston 26 in a manner to be subsequently set forth. At its lower extremity, the sleeve 48 is internally screw threaded for engagement with the upper surface of a cylindrical member 58, this latter member being axially bored, as at 60, for loose sliding engagement upon the tube 36 and counterbored at its upper ex-

tremity, as at 62, for the reception of a packing means 64 retained by a packing gland 66. The packing gland 66 and packing 64 serve to maintain a fluid-tight seal between the cylindrical member 58 and the tubular member 36, upon which the unit 16 and the member 58 slide. At its lower portion, the bore 60 is counterbored, as at 68, for screw-threaded engagement by a depending tube or sleeve 70 which slidably and snugly embraces the tubular member 36 for a purpose to be later set forth. At its lower extremity, tube 70 is threaded to engage the internally threaded, upper portion of an axial bore of a sleeve 72, channeled or scalloped on its upper edge at 73, for establishing a continuous passage between passage 98 and the port 116, the lower portion of whose bore receives a packing means 74 retained as by a packing gland 76. The packing gland 76 has the major and lower portion of its bore 78 filled with a packing or sealing material, as at 80, which is retained therein in compressed relation by a packing gland 82. It will be thus seen that the cylindrical members 72 and 76 which are attached to and relatively slidable with the depending tube 70 are provided with a double packing means in sliding and sealing engagement with the axial depending tube 36.

Attention is now directed again to member 58. The latter is enlarged intermediate its length to provide a shoulder portion whose lower surface is beveled or tapered, as at 84, to provide a sealing surface for a purpose to be later set forth. As shown best in Figure 10, the lower surface of member 58 is provided with an annular series of axially extending bores 86 whose upper portions are intersected by radially extending bores 88 communicating with the exterior surface of the lower portion of the member 58 for a purpose to be subsequently set forth.

Attention is now directed, more specifically, to the upper portion of Figure 2, wherein a free-floating, annular, disk-like piston 90 is disposed within the cylindrical members 46 and 48 and is provided with a packing 92 upon its exterior surface for sealing engagement with the interior walls of said cylindrical members and is further provided with an annular, internal packing 94 adapted for sealing engagement with the axial tubular member 22. The piston 90 constitutes an annular piston in the annular chamber between the tubular member 22 and the interior cylindrical surface of the sleeves 46 and 48 and defines, below the piston 90 and above the piston member 26, a hydraulic chamber of variable size for a purpose to be later set forth. The lower cylinder 48 defines, by its internal surface, a lower hydraulic chamber within which reciprocates vertically the piston 26 between the limits defined by the ribs 56 of the bushing 50 and the abutting action of the packing gland 32 upon the cap or plug member 66.

Attention is next directed to the sealing member 18 best indicated in Figures 2, 3 and 6. The sealing member is composed of an axial tube or sleeve 96 constituting an arbor which is spaced from the tubular member 70 to provide an annular passage 98 therebetween for a purpose to be later set forth. Mounted to envelope and surround the arbor 96 are a plurality of annular rubber sealing units 100, although any other material may be employed which is of a compressible and elastic nature, and will otherwise meet the extreme conditions imposed upon the same. These units, indicated individually at 100, have metallic washers 103 vulcanized to their upper

and lower surfaces for the purpose of limiting the zones of distortion of the same in a manner to be later set forth. The units 100 are retained upon the arbor 96 by means of a collar 102 screw-threadedly engaging the upper end of the arbor and by a collar 104 loosely positioned upon the lower end of the arbor, and retained thereon as by a gland 106 having radial ribs 107 for guiding engagement on tube 70, and screw-threadedly engaging the arbor 96, as shown in Fig. 3. By means of proper adjustment of the collars 102 and 106, the packing units 100 may be given a predetermined amount of compression and radial expansion in order to conform to a given situation. At its upper end, the collar 102 is provided, upon its internal surface, with a packing means 108 retained by a packing gland 110, whose upper surface is beveled as at 112 in conformity with the sealing surface 84. Attached to the lower end of the collar 104, as by internal screw threads, is a depending anchor or tail pipe 114 which is apertured intermediate its length as at 116, and is provided with a cap or closure at its lower end, as at 118. The length of the anchor pipe 114 is so chosen and adjusted that when the lower end thereof 118 rests upon the bottom of the well or bore, the packing elements 100 will be positioned at the desired height or location in the well bore.

At this point, attention is again directed to the piston member 26, as shown in Figure 2 and Figure 9. An annular series of bores 120 in axial planes are provided in the piston 26 connecting the upper and lower surfaces thereof and the lower ends of these bores terminate in enlarged portions receiving ball check valves 122 retained in their upper and closed position against the exit of the bores 120 by means of coil springs 124, the latter being retained by an annular ring 126. The passages 120 constitute bypass means for the piston 26, which permits flow of fluid from above the piston to the chamber beneath the piston when the piston ascends, but close to prevent return flow and therefore check the descent of the piston. As shown best at 128 in Figure 9, a further series of axially extending, annularly spaced bores 128 are provided between the bores 120, and these constitute passageways connecting the hydraulic chambers above and below the piston 26. The passageways 128 are of such diameter that they constitute a restricted, limited leakage means to slowly permit flow of hydraulic fluid from the chamber beneath the piston to that above the piston as the latter descends within the chambers. It will therefore be seen that by this construction, the descent of piston 26 in the hydraulic chamber requires a predetermined time, while the upward travel of the piston is instantaneously permitted by opening of the check valves 122.

The functioning of my device is as follows. The assembled device, as shown in Figure 1, and attached to the lower end of a drill stem, not shown, is lowered into a well bore or casing, after the predetermined length of anchor or tail pipe 114 has been attached to the lower end of the sealing unit 18. As soon as the lower end 118 of the anchor pipe engages the bottom of the well bore, the device automatically begins to operate. By means of the seating of member 118 upon the bottom of the bore, the tail pipe, and consequently the sealing unit, become stationary and cease their downward travel. It will be readily understood that the sealing elements possess the greatest overall diameter of any of the three units above described but still provide considerable

clearance with the walls of the bore of the well 12. Consequently, as the unit or device is lowered in the well, the drilling mud which fills the same is free to pass about the external surface of the 5 sealing means without retarding, appreciably, the descent of the same. As the axial tubular member 14, and the surrounding intermediate member 16 carried thereby, is further lowered or pressed downwardly into the well bore by means 10 of their weight and the weight of the tubular drill stem, not shown, attached to the upper end thereof, the piston 26, by means of the trapped fluid beneath the same and within the sleeve member 48, slowly urges the member 58 downwardly until such time as the beveled seating surface 84 is in sealing engagement with the beveled surface 112. Prior to this time, the annular passageway 98 within the arbor 96 has been 15 in continuous and open communication with the drilling mud in the well casing 12 upon both sides of the sealing elements 100 by means of the passageways 86 and 88 at the upper end thereof. As soon as the surface 84 seats upon the surface 112, the weight of the drill stem transmitted through 20 piston 26 and the hydraulic chamber below the piston and through the member 58, is directly transmitted to the collar 102 and thence through the sealing elements 100 to the collar 104 which rests directly upon the stationary tail pipe 114. 25 As this pressure increases, and as the arbor 96 is free to slide within the sealing elements 100 and through the lower collar 104, the weight of the drilling stem causes a downward deformation and radially outward expansion of the sealing elements 100 until they engage the walls of the well bore 12, as shown best in Figure 8. An efficient sealing engagement is thus established at a plurality of spaced zones between the sealing elements and the wall of the bore, and these ones 30 may be of various widths and spacing, thus dividing the well bore into upper and lower compartments which are effectively sealed from each other. In order to prevent too great a strain and too much wear upon the sealing or packing elements 100, by imposing the entire and very considerable load of the weight of all of the drill stem on the same, a safety or limiting means is provided, this means comprising the usual weight indicating gauge attached to the drill stem cable 35 at the surface of the ground. When this gauge shows a predetermined tension on the drill stem cable, further lowering movement is halted. However, owing to the leakage passages or bores 128, 40 further downward movement of the axial tubular member 14 is still permitted and the piston 26 and the depending tube 36 slowly travel downwardly until the lower surface of piston 26 rests upon the upper surface of packing gland 66. During 45 this last portion of the downward movement of the tubular member 36, the ports 38 descend past the packing members 74 and 80, and are uncovered below the latter member, so that complete communication is established between the interior of the tubular drill stem, not shown, the member 22, the bore 34 of piston 26, the tubular member 36, port 38, the interior of the tail pipe 114, and the aperture 116 to the chamber in the well bore below the sealing means 100. During 50 this time, suitable measurements and tests may be made through this passageway now established from the interior of the seal-off portion of the well bore, with a view to determining its productive capacity as to pressure, volume, nature of material, and the like, and for the purpose of

obtaining a sample of the production of the formation.

It will be understood, that during the downward travel of my device in the well bore, the drilling mud found therein will have free access by means of the passage 54 to the upper side of the floating piston 90, thereby imposing a gradually increasing load upon the hydraulic fluid contained between the floating piston and the upper end of the piston 26, to thereby impose a load upon the member 58 and maintain the sealing engagement between surfaces 84 and 112. The downwardly extended position of the axial tubular member 14, during which the valve port 38 is opened, is fully illustrated in Figure 7. The position of the parts shown in Figures 2 and 3 represents generally the position assumed by the parts during the downward travel and insertion of the device in the well bore, and before the automatic operation has been initiated, with the exception that the showing in Figure 3 represents the limit of the downward travel of the arbor 96 and the member 106 relative to the tail pipe 114. I desire to call attention to the fact that the rate of leakage through the passageways 128 is preferably chosen to require from two to five minutes before the piston 26 has sufficiently completed its descent within the cylinder 48, to effect an opening of the port 38. This time delay has the very useful function of preventing a premature opening of the valve port 38 before the device has become seated in the bottom of the well. For instance, if the cap member 118 should hit an obstruction in the well, a sufficient length of time is required for the completion of the automatic operation of the device as to sealing the bore and opening the sampling ports, to permit the rapid raising and lowering of the drilling stem and the device in order to break away the obstruction, it being understood that upon raising the member 14 immediately causes piston 26 to travel to the top of its cylinder in member 16, as above set forth.

When the tests are completed and it is desired to remove the device, the initial upward movement of the drilling stem and of the axial tubular member 14 first closes the sampling port 38, the sealing means being still retained in sealed position by means of the weight of the drilling mud as transmitted through the passageway 54, piston 90, hydraulic chamber in the sleeve 46, piston 26, hydraulic chamber in sleeve 48, member 58, and collar 102. This weight prevents premature lifting of the intermediate member and premature releasing of the sealing engagement as when the tube 22 starts to raise, beginning to close the sampling valve 38. Continued upward movement of the axial tubular member next lifts the piston 26, which, by means of the check valve 122, is now freely slidable upwardly in the sleeve 46, until the upper end of the piston engages the ribs 56. At this point, the valve 38 is now fully closed, and continued upward travel of piston 26 lifts the intermediate member, breaking the seal between the surfaces 84 and 112, and eventually opening the passageways 86 and 88, permitting free flow or communication through the bypass 98 about the sealing unit 100. At this moment, the pressure causing the distortion of the sealing units and their sealing engagement with the well bore is released and the sealing units returned to their normal dimensions, whereupon the entire device is readily withdrawn from the well.

In view of the foregoing description taken in conjunction with the accompanying drawings, it

is believed that a clear understanding of the construction, operation and advantages of the device will be quite apparent to those skilled in this art.

Particular attention is now directed to the double sealing means 74 and 80 which is an extremely important part of the successful operation of the invention. When the tester is lowered and just beginning to seat, the interior of the drill stem 10 and the tubular member 14 is at substantially atmospheric pressure. The pressure in the bore of the well, at the moment of opening valve ports 38 is extremely high, even as much as thousands of pounds per square inch. As the ports 38 pass the lower edge of seal 80 to the position of Fig. 7, the difference of pressure causes an inflow of gas, mud, etc., from the well bore below the sealing members 100 with the interior of tube 36. The velocity and pressure differential of this flow almost invariably corrodes, abrades and destroys the effectiveness of the packing means at that point. Consequently, packing 80 is no longer capable of sealing the ports 38 when the tester is closed for withdrawal. Therefore, the upper packing 74 is relied upon to establish the sealing engagement of tube 36 and ports 38 for trapping a sample in tube 36 during the withdrawal.

Obviously, the lower seal 80 would necessarily be replaced after each operation of the device. As will be apparent, a series of successive seals similar to 74 and 80 may be incorporated if desired.

It is to be understood, however, that even though I have herein shown and described a preferred embodiment of my invention that the same is susceptible to certain changes fully comprehended by the spirit of the invention as herein described and within the scope of the appended claims.

I claim as my invention:

1. An attachment for testing the productive capacity of deep wells including an axial tubular member engageable with a tubular drilling stem, a concentric member supported by and slidable longitudinally of said axial member, an outer sealing member slidably supported upon said concentric member, means establishing open communication between the interior and exterior of the sealing member, and a valved passage in said axial member establishing communication between the exterior of said concentric member and the interior of said axial member, and actuating means controlling said valved passage, said actuating means including a hydraulic chamber interposed between said axial member and said concentric member for transmitting thrust therebetween, said hydraulic chamber consisting of a piston carried by said axial member and a cylinder carried by said concentric member, a floating packing slidable in said cylinder and upon said axial member and means establishing open communication between the outer side of said packing and the exterior of said cylinder.

2. An attachment for testing the productive capacity of deep wells including an axial tubular member engageable with a tubular drilling stem, a concentric member supported by and slidable longitudinally of said axial member, an outer sealing member slidably supported upon said concentric member, means establishing open communication between the interior and exterior of the sealing member, and a valved passage in said axial member establishing communication between the exterior of said concentric member and the interior of said axial member, and actuat-

ing means controlling said valved passage, said actuating means including a hydraulic chamber interposed between said axial member and said concentric member for transmitting thrust therebetween, said hydraulic chamber consisting of a piston carried by said axial member and a cylinder carried by said concentric member, a floating packing slidable in said cylinder and upon said axial member, and means for subjecting the upper surface of said floating packing to the pressure existing exteriorly of the attachment.

3. The combination of claim 2 wherein said sealing member includes spaced deformable members radially expansible to engage the wall of a bore and seal a portion thereof.

4. The combination of claim 3 and means carried by said sealing member for adjusting the expansion of said deformable members.

5. The combination of claim 2 wherein said sealing member includes a tail pipe having a first collar vertically adjustable upon the upper end thereof, an arbor slidable in said first collar, a second collar vertically adjustable upon the upper end of said arbor, and spaced deformable members about said arbor and interposed between said first and second collars.

6. The combination of claim 5 wherein said arbor includes an annular passage and said concentric member includes a lower portion slidably received in said second collar having a conduit terminally communicating with said annular passage and the interior of a well bore.

7. The combination of claim 6 and means for closing said passage and conduit.

8. The combination of claim 7 wherein said means includes a valve carried by said lower portion and a seat carried by said second collar for receiving said valve.

9. The combination of claim 8 wherein said valve includes a shoulder on said lower portion above said conduit and said valve seat includes an annular recess in the upper end of said second collar.

10. The combination of claim 1 wherein said sealing member includes spaced deformable members radially expansible to engage the wall of a bore and seal a portion thereof.

11. The combination of claim 10 and means carried by said sealing member for adjusting the expansion of said deformable members.

12. The combination of claim 1 wherein said sealing member includes a tail pipe having a first collar vertically adjustable upon the upper end thereof, an arbor slidable in said first collar, a second collar vertically adjustable upon the upper end of said arbor, and spaced deformable members about said arbor and interposed between said first and second collars.

13. The combination of claim 12 wherein said arbor includes an annular passage and said concentric member includes a lower portion slidably received in said second collar having a conduit terminally communicating with said annular passage and the interior of a well bore.

14. The combination of claim 13 and means for closing said passage and conduit.

15. The combination of claim 14 wherein said means includes a valve carried by said lower portion and a seat carried by said second collar for receiving said valve.

16. The combination of claim 9 wherein said means includes a valve carried by said lower portion and a seat carried by said second collar for receiving said valve.

17. An attachment for testing the productive capacity of deep wells including an axial tubular member engageable with a tubular drilling stem, a concentric member supported by and slidably longitudinally of said axial member, an outer sealing member slidably supported upon said concentric member, means establishing open communication between the interior and exterior of the sealing member, and a valved passage in said axial member establishing communication between the exterior of said concentric member and the interior of said axial member, and actuating means controlling said valved passage, said actuating means including a hydraulic chamber interposed between said axial member and said concentric member for transmitting thrust therebetween, said hydraulic chamber consisting of a piston carried by said axial member and a cylinder carried by said concentric member, a floating packing slidable in said cylinder and upon said axial member, means for subjecting the upper surface of said floating packing to the pressure existing exteriorly of the attachment, and means for effecting relatively rapid flow of hydraulic fluid past the piston upon movement of the piston in one direction and for effecting relatively slow flow of hydraulic fluid past the piston upon movement of the piston in the opposite direction.

18. The combination of claim 17 wherein said last mentioned means includes a first series of bores extending through said piston from the top to the bottom thereof, one way check valves positioned in said bores, and a second series of bores of lesser diameter than the bores in said first series extending through said piston from the top to the bottom thereof.

19. An attachment for testing the productive capacity of deep wells including an axial tubular member engageable with a tubular drilling stem, a concentric member supported by and slidably longitudinally of said axial member, an outer sealing member slidably supported upon said concentric member, means establishing open communication between the interior and exterior of the sealing member, a valved passage in said axial member establishing communication between the exterior of said concentric member and the interior of said axial member, and actuating means controlling said valved passage, said actuating means including a hydraulic chamber interposed between said axial member and said concentric member for transmitting thrust therebetween, said hydraulic chamber consisting of a piston carried by said axial member and a cylinder carried by said concentric member, a floating packing slidable in said cylinder and upon said axial member means establishing open communication between the outer side of said packing and the exterior of said cylinder, means for effecting relatively rapid flow of hydraulic fluid past the piston upon movement of the piston in one direction and for effecting relatively slow flow of hydraulic fluid past the piston upon movement of the piston in the opposite direction.

20. The combination of claim 19 wherein said last mentioned means includes a first series of bores extending through said piston from the top to the bottom thereof, one way check valves positioned in said bores, and a second series of bores of lesser diameter than the bores in said first series extending through said piston from the top to the bottom thereof.

21. An attachment for testing the productive capacity of deep wells including an axial tubular member engageable with a tubular drilling

11

stem, a concentric member supported by and slideable longitudinally of said axial member, an outer sealing member slidably supported upon said concentric member, means establishing open communication between the interior and exterior of the sealing member, a valve passage in said axial member establishing communication between the exterior of said concentric member and the interior of said axial member, actuating means controlling said valved passage, said actuating means including a hydraulic chamber interposed between said axial member and said concentric member for transmitting thrust therebetween, said hydraulic chamber consisting of a piston carried by said axial member and a cylinder carried by said concentric member, a floating packing slideable in said cylinder and upon said axial member, means for subjecting the upper surface of said floating packing to the pressure existing exteriorly of the attachment, means for effecting relatively rapid flow of hydraulic fluid past the piston upon movement of the piston in one direction and for effecting relatively slow flow of hydraulic fluid past the piston upon movement of the piston in the opposite direction, said sealing member including a tail pipe having a first collar vertically adjustable upon the upper end thereof, an arbor slideable in said first collar, a second collar vertically adjustable upon the upper end of said arbor, and spaced deformable members about said arbor and interposed between said first and second collars.

22. The combination of claim 21 wherein said

5
10
15

12

arbor includes an annular passage and said concentric member includes a lower portion slidably received in said second collar having a conduit terminally communicating with said annular passage and the interior of a well bore.

23. The combination of claim 22 and means for closing said passage and conduit.

24. The combination of claim 23 wherein said means includes a valve carried by said lower portion and a seat carried by said second collar for receiving said valve.

25. The combination of claim 24 wherein said valve includes a shoulder on said lower portion above said conduit and said valve seat includes an annular recess in the upper end of said second collar.

26. The combination of claim 25 wherein said last-mentioned means includes a first series of bores extending through said piston from the top to the bottom thereof, one way check valves positioned in said bores, and a second series of bores of lesser diameter than the bores in said first series extending through said piston from the top to the bottom thereof.

25 LEO COURTER.
